UNITED STATES PATENT OFFICE.

GRANVILLE BRADSHAW, OF LONDON, ENGLAND.

BOWLING-GAME APPARATUS.

Application filed March 8, 1927, Serial No. 173,726, and in Great Britain May 6, 1925.

This invention relates to certain new and useful improvements in game apparatus of the class having targets which when struck by an object will be moved to release actuating means for indicators.

The object of the invention is to provide a game apparatus which embodies an alley, targets which are moved when struck by a manually thrown object, the targets being coordinated with means for releasing particular indicators which upon being released present to view symbols carried by said indicators.

An apparatus constructed in accord with the invention provides a game apparatus and combined therewith advertising means operatively maintained so that when a target is struck, power actuating means will be released to move an indicator, the target being of such character as to form a continuation when struck of the alley bed in order that the missile actuating the target will be guided into a receptacle connected with a return runway.

The invention consists of game apparatus which embodies an alley, targets which are pivoted below and beyond the end of the alley bed, a structure beyond the end of the alley bed constructed to receive missiles or balls, and an upright structure which maintains indicators and actuating means therefor, said actuating means being associated with indicators which are in cooperative relation with the targets.

The invention further consists in the construction, arrangement and combination of parts as hereinafter set forth, combined with means for returning to operative position the targets and indicators.

In the accompanying drawings,—

Figure 1 is a longitudinal section of a game apparatus constructed in accordance with the invention;

Figure 2 is a detail sectional view of one of the targets;

Figure 3 is a rear elevation of indicators as are used with the structure illustrated by Fig. 1;

Figure 4 illustrates a fragmentary sectional view of a modification of the invention; and

Figure 5 is a detail front elevation of a type of indicator used with the structure illustrated by Fig. 4.

The game apparatus illustrated is designed to provide indicators or figure dis-

playing elements which are controlled by striking and moving a target, and this game playing and advertising device embodies structural features which include targets which are pivotally maintained below the plane and beyond the end of an alley, the connections being such that when the target is struck, for instance, by a bowling ball, it will assume a horizontal position and serve, when in such position, as a continuation of the alley of a length sufficient to overlie a pocket or receptacle for bowling balls or the like. The structure embodies means for retaining the target in horizontal position, as well as in vertical position, by engagement with a catch maintained by a shaft located forward of and below the shaft which carries the targets, the apparatus also having means which when actuated will reset the targets and indicators.

The invention further consists in providing means for actuating individual indicators released for exposure when a target is struck.

An amusement apparatus constructed to accord with my invention has a bowling alley or floor of suitable length and width, the floor of the alley 1 being inclined longitudinally from the player's end upward to the target end, and below the floor and to one side thereof is a runway to receive balls which have been played. Targets 2 are mounted upon a transverse shaft 3 located forward of and below the front end of the alley bed and upon the shaft 3 is rigidly secured a rearwardly extending projection or arm 4, and at right angles thereto there is formed upon the target 2 an extension 5. Below and forward of the shaft 3 is maintained a shaft 7 which carries a series of rigidly attached stop lugs 6, the same being in the path of the projections 4 and 5. The shafts are each provided with a drum or disk which is engaged by a connection for manually moving the shaft having the projections 6 to effect a turn of the targets to an elevated position and for holding the shaft against rotation when the target is in a horizontal position.

As shown by Fig. 1, the shaft 7 is turned in one direction by a driven belt 8 on a shaft 9 having a pulley over which is passed a belt 10. The belt also engages a pulley on a shaft 11, said shaft having a series of spaced cams 12 for engagement with projections on crossed arms 13, said arms being pivoted

upon a support 14, a spring being carried by said support for holding the arms in position to be engaged by their respective cams 12. As illustrated by Figs. 1 and 3, rotatably mounted indicators or signs 15 are carried by shafts 16 and coiled springs 17 are attached to the shafts 16 and are of such configuration that one end of the springs engages the signs or indicators to effect rotation of the same individually and simultaneously with movement of the target from a vertical position to a horizontal position, which it assumes when struck by a missile.

The indicators 15 are preferably provided with laterally projecting lugs 15^A which are positioned to overlie an adjacent indicator, the purpose of the lugs being to prevent rotation of the next indicator thereto. The shaft 11 having the cams 12 thereon is actuated by a drum carried by the shaft and about which is passed a flexible connection 18 to which is attached a weight 19, and when the shaft 11 is rotated, the cams 12 which project from the shaft will engage with protuberances on the arms 13. These arms cross each other and each is simultaneously moved by a spring carried by the support 14, the ends of the spring engaging the arms 13. Movement of the arms is restricted by engagement with the collars of the cams 12, and the ends of the arms are provided with notches 13^A, a projecting portion of the notches being engaged by the opposite edges of the indicators, the indicators in operation turning in the direction of the arrows shown in Fig. 1. The shafts 16 which carry the indicators are provided with pulleys or sheaves which are connected by a cross belt. The lower shaft 16 is also provided with a sheave or drum from which extends a flexible connection attached to manually operated means for turning the indicators and at the same time winding the turning springs therefor.

The structure shown in Fig. 2 is such that when a target 2 is struck by a ball, the projection 5 will be moved out of engagement with a stop 6, when the impact and weight of the ball will move the target to a horizontal position, and when in such position, it will overlie a pocket 20, which pocket communicates with the usual runway, returning the balls to the front end of the alley bed.

When a target is in a horizontal position, it will be retained in such position by gravity and the projection 5 will act as a stop by engagement with the under side of the forward end of the alley, and when in a horizontal position, the projection 4, which is properly spaced on the shaft 3 will be engaged by a projection 6 on the shaft 7 which is connected with the endless belt 8, one of the pulleys therefor being driven by the belt 10 which moves the shaft 11 so that a par-

ticular cam will release an arm 13 and permit a semi-rotation of one of the indicators 15 to expose a character, figure or marking thereon. The individual indicator so released is turned on its supporting shaft 16 by a spring 17, the indicator remaining in such position until reset by manual operation of a lever having several connections for operating certain parts.

Adjacent to the rear or player's end of the runway 21 into which balls are deposited from the pocket 20, there is fulcrumed a lever 22 having a segment or quadrant 22^A, the lever also being connected to arms which carry a stop 23 for balls before they reach the end of the runway. The stop 23 is of such construction as to permit the passage of balls beneath the same and between the arms to which the stop is attached. The segment or quadrant to which the lever is attached has attached thereto a plurality of flexible connections as cords or wires. One of the connections 24 extends from an end of the arcuate segment 22^A to a pulley on the shaft 3 for moving the targets to a vertical position, and the opposite end of the segment has secured thereto a flexible connection 25 for moving a pulley on shaft 7 to position the stop lugs 6 so that they will be out of the path of the arm 4 and projection 5 of the target. Rotation of the shaft 7 moves an endless belt 8 which drives a belt 10 and pulley on shaft 11 to rewind a cord 18 to which is attached the weight 19. A connection 25 is connected at one end to the center portion of the segment and a guide pulley and from the pulley to one on the shaft 16 which carries the lower row of indicators, movement of such shaft being transmitted by means of a crossed belt to an upper shaft which carries an upper row of indicators, and by this connection, the indicators may be turned in opposite directions.

By means of the flexible connections, the targets and indicators may be returned to position by the lever to commence a game, and when the upper end of the lever is moved rearward, the balls will be allowed to pass the stop 23, after which the lever will be moved to position shown, when all of the connections as 24, 25 and 26 will be slack.

Figs. 4 and 5 show an alternative embodiment of my invention wherein the rear casing is provided with vertically movable indicators 30 which slide upon guide rods 31 and move by gravity to a position where they will be visible through openings. The indicators have lugs 30^A for determining the order of release thereof, and the indicators are supported by rock levers 32 carried by a transverse shaft, each lever having attached thereto a flexible connection which is guided through curved tubes 34, the ends of the connections being attached to movable

- catches 33 maintained in position by a spring to be engaged by projections 5 on the target and arms 4 on a shaft 3, as previously described.
5. When the cord 36 is drawn, the targets will be restored to vertical position and by pulling on the cord 35, the indicators will be raised.
- In practice, the inclined alley and vertical structure at its rear may be of any desired width to accord with the width of the targets and indicators.
- The apparatus is of such construction that when a target is struck or moved to a horizontal position, a corresponding indicator will be displayed, and in use, there will be a predetermined arrangement of the parts to vary the order in which the targets are to be moved. Further, with the device shown, a player may be allowed a certain number of balls which may be counted before or after resetting the targets and indicators.
- It will be noted that the alley inclines upward from the player's end to the target end; also that the targets are connected to supports located below and beyond the end of the alley and form a continuation or extension thereof when in a horizontal position. Also, the balls drop in a pocket from the targets, and the resetting of the targets and the indicators is effected by movement of a single lever which also functions to hold played balls beyond reach of the players until the resetting lever is moved.
35. The indicators may have thereon either letters, figures or numerals, and the cams which control the release of the holding arms may be set to vary the release thereof, respective to a target struck.
40. It will also be noted that the targets may be released by a very slight contact with a ball or missile and that the inclined alley introduces into the game a feature not found in ordinary bowling alleys. Further, the width of the indicators may bear such relation to the width of the targets that a ball may pass through spaces between adjacent targets without striking the same, and various changes may be made as to specific construction of the parts and arrangement thereof.
- I claim:
1. In a bowling game apparatus, an alley bed, a support maintained below one end of the alley bed, targets mounted for movement on the support, projections on the targets for engagement with the under side of the alley bed to form a continuance of the alley bed when the targets are in substantially horizontal position.
  2. In a bowling game apparatus, an alley bed, a receptacle for balls beyond one end of the alley bed, a support for targets, targets mounted on the support, each target having a projecting portion for engagement with the alley bed to maintain a target in position to horizontally span a space between the alley bed and the receptacle for balls.
  3. In a bowling game apparatus, an alley bed, a shaft for targets below the alley bed, projections fixedly attached to the shaft, targets mounted for movement upon the shaft, projections on the targets for engagement with the under side of the end portion of the alley bed when a target is in substantially horizontal position, projections which are maintained in positive engagement with said shaft, a driven shaft maintained adjacent to the shaft having targets thereon, projections on the driven shaft for engagement with the projections on the targets and on the shaft, the projections when in engagement restricting rotation of the driven shaft.
  4. In a bowling game apparatus, an alley bed, a target supporting shaft having projections fixedly attached thereto, targets maintained in movement engagement with said shaft, projections on the targets, a driven shaft provided with a pair of diverging projections for engagement with projections on the target supporting shaft and with the projections on the targets, movable indicators, and means for releasing the indicators operative upon movement of the driven shaft.
  5. In a bowling game apparatus, an alley bed, shaft supports, shafts maintained by the supports and located below and beyond an end of the alley bed, targets mounted for movement upon one of the shafts, projections which extend from the targets, projections fixedly attached to the shaft which carries the targets, a driven shaft below the target carrying shaft, projections thereon which are in line with the projections on the target carrying shaft, gravity operated means for moving the driven shaft a predetermined distance during movement of the target, in combination with a plurality of movable indicators which are engaged by movement means for holding the same against movement, except during the period of movement of a target, and manually operated means for simultaneously restoring the targets and the indicators to initial position.
  6. In a bowling game apparatus of the character set forth, the combination of a plurality of targets and a corresponding plurality of indicators, projections on indicators for engagement with an adjacent indicator operating to prevent movement of the engaged indicator until a release thereof has been effected by the actuation of a target.
  7. The combination in a bowling game apparatus, an alley bed, a return way for balls, targets pivotally supported beyond and below one end of the alley bed and adapted to be moved by impact to position to form an

4
extension of the alley bed, a receptacle for balls, a ball return way, a lever having ball engaging means movable with the lever to a position which serves as a stop for balls and upon rearward movement of the lever to a position whereby the balls may pass beyond the stop.

8. In a bowling game having movable targets and releasable indicators, releasing means for said indicators connected to said targets, said releasing means comprising spring actuated means which engage with the indicators to hold the same against movement, and a shaft having a plurality of projections thereon for engagement with the holding means to effect a release of an indicator operated by a change of position of a target.

9. In a bowling game, an alley bed, a shaft located below and beyond one end of the alley bed, a series of projections which are

fixedly attached to the shaft, a series of targets mounted for movement on the shaft, projections on the targets which are adapted to engage with the under side of the alley bed to restrict movement of the target beyond a horizontal position, a driven shaft having projections for engagement with the projections on the targets and the shaft, the parts being associated to permit movement of the driven shaft during change of position of a target from a vertical to a horizontal position, in combination with a plurality of movable indicators, means for restricting movement of the indicators, said means being actuated by a release of the driven shaft effective during movement of a target from a vertical to a horizontal position.

In witness whereof I have signed this specification.

GRANVILLE BRADSHAW.
